NEEDLE HUB

Theodore H. Gewecke, Glenview, Ill., assignor to
Baxter Laboratories, Inc.

Application May 21, 1954, Serial No. 431,542

7 Claims. (Cl. 128—214)

This invention relates to a needle hub and, more particularly, to a needle hub adapted for attaching a plug-in needle to the tubing of a parenteral transfusion set.

In the process of withdrawing blood from a donor and conducting it to a storage vessel for later use, it has been the practice to employ an evacuated system to facilitate the removal of blood. This is achieved by providing an evacuated container which is adapted to be connected to a vein of the donor by means of a transfusion set. A set ordinarily consists of a length of tubing capable of withstanding external atmospheric pressure when its interior is evacuated, and a pair of needles affixed to the ends of the tubing, permitting vena-puncture of the donor and puncture of the plug of the evacuated container. It is important that these needles be very tightly and securely attached to the tubing in order to preserve the vacuum existing within the transfusion system. Because of the difference in the diameters of the tubing and the needles, it is also necessary to incorporate a reducing feature of some kind into the needle hubs that connect the needles to the tubing.

Previously, expedients for making these reducing connections airtight have consisted of providing a solder seal about the juncture of the needle with the reducer hub and the further expedient of tightly clamping the tubing, which is generally of a flexible nature, to the outside of the reducer hub.

In the past a further problem has existed in the design of the plug-in needle hub. This problem resulted from the fact that puncture area of the stopper was required to be of substantial thickness in order to cause the puncture to re-seal itself upon removal of the plug-in needle, and, therefore, considerable pressure had to be applied to the plug-in needle to cause it to penetrate the aforementioned thick plug. A plug closure of this type is described in Wayne D. Brandon Patent No. 2,457,120, issued December 28, 1948.

One expedient which resulted in easier puncture was to provide a flange about the needle against which pressure could be exerted. This proved inadequate because it was difficult to remove the needle at the end of the blood donation inasmuch as there was no corresponding flange against which "pull out" pressure could be applied. As a consequence, the attendant would manipulate the plug-in needle back and forth in an effort to dislodge it. These efforts often would enlarge the puncture to such an extent that it was frequently impossible for the puncture to seal itself. The expedient of limiting the insertion of the needle so as to provide adequate space under the flange for insertion of the attendant's fingers to pull out the plug-in needle proved unsatisfactory because a longer needle was required, thereby increasing the cost of a set.

By the plug-in needle hub of my invention, I am able to provide a ready means for gripping the plug-in needle both for puncturing the thick plug and removal of the needle therefrom. In addition, I am able to tightly connect the tube to the needle at minimum cost of parts

and minimum operations of labor, thereby achieving substantial savings in the production of an expendable transfusion set suitable for transfusion of donated blood.

My invention will be explained in conjunction with the accompanying drawing, in which Fig. 1 is an elevational view of a blood transfusion container shown in combination with a transfusion set which has been provided with the needle hubs of my invention; Fig. 2 is an elevational view partially in cross-section showing one form of the hub of my invention; Fig. 3 is an enlarged cross-sectional view similar to Figure 2 showing a modified form of connector with tubing and needle secured thereto; and Fig. 4 is an elevational view partially in cross-section showing a modified form of the needle hub of my invention especially suitable for use with the needle adapted for insertion into the blood donor.

Referring to the drawings and, in particular, Fig. 1, a blood collection container is generally designated 10. Container 10 includes a glass-body portion 11, band 12, bail 13, and closure 14. In usual practice, container 10 is mounted by means of bail 13 in mouth downward condition. Before use, container 10 is partially evacuated in order to aspirate the blood from the vein of the donor. It also contains a suitable amount of anti-coagulant solution. Transfusion set B includes tubing 15, plug-in needle 16, and donor needle 17. Some type of clamping means such as hemostat C is generally used to clamp tubing 15 in order to preserve the vacuum in container 10 during puncture of closure 14. After donor needle 17 has been inserted into the vein of the donor and plug-in needle 16 is inserted into the rubber closure plug 14 so as to communicate with the interior of glass container 11, hemostat C is unclamped and the transfusion operation is begun. Plug-in needle 16 is attached to tubing 15 by means of reducing hub 18, shown in enlarged form in Fig. 2. Donor needle 17 is attached to tubing 15 by means of hub 19, shown in enlarged form in Fig. 4.

Referring now to Fig. 2, numeral 18 designates generally a needle hub. The hub includes a tubular body portion 20 having outwardly flared end portions 21. Disposed axially with respect to body portion 20 is inner tubular portion 22. Integral with body portion 20 and tubular portion 22 is transverse wall portion 23. Wall portion 23 maintains inner tubular portion 22 in axial relation to body portion 20. In the embodiment shown in Fig. 2, the connection of transverse wall 23 with tubular portion 22 is approximately midway the length of tubular portion 22.

The type of hub outlined can be cheaply made by casting, thereby further reducing the cost of parts in an expendable transfusion set.

Tubular portion 22 is hollow, and the hollow portion 24 thereof is adapted to receive a parenteral needle 16. Annular space 25 is provided by spacing body portion 20 from tubular portion 22.

Hub 18 is incorporated into administration set B by inserting needle 16 into the hollow portion 24 of inner tubular portion 22 and by inserting tubing 15 in the annular space 25 achieved by spacing body portion 20 from inner tubular portion 22. As shown in Fig. 2, a tight securing of needle 16 to hub 18 and tubing 15 to hub 18 is achieved by clamping. In practice, it has been found that a swaging operation effects air-tight joints. However, any mechanical operation capable of radially compressing portions of hub 18 are suitable to achieve the desired clamping.

Swaging the lower part of inner tubular portion 22 as at 26 provides an air-tight seal of needle 16 to hub 18. Swaging the wall portion of body 20 compresses tubing 15 between it and the upwardly extending part of inner

tubular portion 22 as at 26a. It is to be noted that the upwardly extending part of inner tubular portion is also radially compressed as at 26b to provide a second seal between needle 16 and hub 18. Thus, two seals must be broken for air to enter the administration set by way of my puncture hub. For air to enter the administration set from the tubing side of hub 18 it must pass through seals at 26a and 26b. From the needle side it must pass through seals 26 and 26b. However, it is not essential that needle 16 be in air-tight engagement with tubular portion 22 at the two points indicated.

It is to be noted that the tubular portion 22 is characterized by a superior resistance to radially compressive deformation than is the body portion 20 in order to achieve a tight fitting engagement between hub 18 and tubing 15. In a similar fashion, the resistance to radially compressive deformation of tubular portion 22 is less than that present in needle 16, thereby preventing collapse or substantial deformation of needle 16 by the squeezing operation.

Another form of connector is shown in Fig. 3, which is especially adapted to connect large diameter tubing to a needle. This is achieved by using a series of reducers. Essentially, the connector includes a body portion 20' with flared ends 21', much the same as in the embodiment shown in Fig. 2. Primed numerals are used in the description of this element, showing thereby the similarity in the two forms of my invention. As also shown in Fig. 2, the connector includes an integral tubular portion 22' axially disposed with respect to tubular body portion 20' and maintained in such axial relation by means of integral transverse wall portion 23'. An essential difference between the embodiment shown in Fig. 3 and that shown in Fig. 2 is that the transverse wall portion 23' is connected to tubular portion 22' at the extreme end of tubular portion 22' rather than about midway, as shown in Fig. 2. The surface of wall 23' is opposite the surface to which tubular portion 22' is connected and is provided with a central recessed portion 27'.

Needle 16' is secured to the connector hub by swaging at 24', as outlined above. Tubing 15' of transfusion set B is secured to connector by means of reducing sleeve 28', which is inserted into recessed portion 27' and is crimped therein by grooving of the upper surface of wall 23' as at 29'. The fit by the reducer 28' which, in the preferred embodiment, is of a plastic material and tubing 15' is made tight by means of introducing a plastic solvent material between the fitting surfaces and causing these surfaces to become welded together.

A modified form of the connector of my invention is shown in Fig. 4, which is essentially the same form as that shown in Fig. 2 but without flared end portions, thereby particularly adapting it for use as the donor insertion needle. It is apparent that flared ends would prevent a substantially parallel insertion of the needle such as is required in order to puncture the patient's vein. This type of hub is also suitable for incorporation into other types of administration sets.

While in the foregoing specification I have set forth

specific steps and procedure as illustrative of my invention in considerable detail, it will be understood that such details may be varied widely by those skilled in the art without departing from the spirit of my invention.

I claim:

1. A needle hub for attaching a plug-in needle to the tubing of a parenteral administration set comprising a tubular body having outwardly flared end portions, a smaller diameter tubular portion axially disposed therein and a transverse wall connecting said tubular portion to said body and maintaining said tubular portion in axial relation to said body.

2. A single piece cast needle hub of the character specified comprising a tubular body having outwardly flared end portions, an integral smaller diameter tubular portion in spaced relation thereto and an integral transverse wall connecting said tubular portion to said body.

3. A needle hub for attaching a plug-in needle to the tubing of a parenteral transfusion set comprising a tubular body having outwardly flared end portions, a smaller diameter hollow tubular portion axially disposed therein whereby an annular space is provided, said tubular portion being adapted to axially receive and peripherally clamp a parenteral needle, and a transverse wall connecting said tubular portion to said body.

4. A needle hub for attaching a plug-in needle to the tubing of a parenteral transfusion set comprising a tubular body having outwardly flared end portions, a smaller diameter hollow tubular portion axially disposed therein whereby an annular space is provided, said tubular portion being adapted to axially receive and peripherally clamp a parenteral needle, and a transverse wall connecting said tubular portion to said body, said tubular body being more resistant to deformation upon application of radially compressive stress than said body but less resistant than said needle.

5. The needle hub as set forth in claim 4 wherein the said transverse wall is connected to the said tubular portion at a point mediate the ends thereof.

40 6. The needle hub of claim 4 wherein the said transverse wall is connected to the said tubular portion at one end thereof.

7. A needle hub of the character specified, comprising a tubular body having outwardly flared end portions, a smaller diameter tubular portion axially disposed therein, and a transverse wall connecting one end of said tubular portion to said body portion, the surface of said wall opposite said tubular portion being provided with a central recessed portion of greater diameter than the internal diameter of said tubular portion.
